US0D1109325S

(12) **United States Design Patent** (10) **Patent No.:** **US D1,109,325 S**
(45) **Date of Patent:** **** Jan. 13, 2026**

(54) **ENDOSCOPE CONNECTOR**

(71) Applicant: **Karl Storz SE & Co. KG**, Tuttlingen (DE)

(72) Inventors: **Anina Cooter**, Goleta, CA (US); **Michael Kloster**, Sturbridge, MA (US); **Evan M. Leingang**, Plymouth, MN (US); **Kevin R. Lochner**, Maple Grove, MN (US); **Indrek-Toomas Polluks**, Rakvere (EE); **Marko Radosevic**, Goleta, CA (US); **Jeremy Roth**, Santa Barbara, CA (US); **Reed O. Saunders**, Minneapolis, MN (US); **Thomas A. Tedham**, Eden Prairie, MN (US); **Richard A. Thompson, II**, St. Louis Park, MN (US); **Chase Van Rossem**, Santa Barbara, CA (US)

(73) Assignee: **Karl Storz SE & Co. KG**, Tuttlingen (DE)

(**) Term: **15 Years**

(21) Appl. No.: **29/930,914**

(22) Filed: **Mar. 4, 2024**

Related U.S. Application Data

(57) **CLAIM**

The ornamental design for an endoscope connector as shown and described.

DESCRIPTION

FIG. 1 illustrates a bottom perspective view of the endoscope connector,
FIG. 2 illustrates a top perspective view of the endoscope connector,
FIG. 3 illustrates a front side view of the endoscope connector,
FIG. 4 illustrates a back side view of the endoscope connector,
FIG. 5 illustrates right side view of the endoscope connector
FIG. 6 illustrates left side view of the endoscope connector,
FIG. 7 illustrates a top view of the endoscope connector; and,
FIG. 8 illustrates a bottom view of the endoscope connector.
The broken lines in the drawings illustrate portions of the endoscope connector, which form no part of the claimed design.

1 Claim, 7 Drawing Sheets

Related U.S. Application Data

division of application No. 17/470,000, filed on Sep. 9, 2021, now Pat. No. 11,883,002.
